(57) **CLAIM**

The ornamental design for a cordless soldering station, as shown and described.

DESCRIPTION

FIG. 1 is a front perspective view of its component 1, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of its component 2;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a rear perspective showing component 2 in a state of use;

FIG. 18 is its a rear perspective showing component 2 in another state of use;

FIG. 19 is a front perspective of component 1 and 2 in a combined state of use;

FIG. 20 is an enlarged detail view of area 20 in FIG. 7;

FIG. 21 is an enlarged detail view of area 21 in FIG. 8; and, FIG. 22 is an enlarged detail view of area 22 in FIG. 10.

The broken lines in the drawings illustrate the portions of the cordless soldering station, which form no part of the claimed design. The dash-dot-dash broken lines encircling the enlarged views are for annotative purposes only and form no part of the claim thereof.
